UNITED STATES PATENT OFFICE.

SAMUEL RUBEN, OF NEW YORK, N. Y.

APPARATUS FOR RECORDING ELECTRICAL SIGNALS.

Application filed June 17, 1922. Serial No. 569,093.

To all whom it may concern:

Be it known that I, SAMUEL RUBEN, citizen of the United States, and resident of New York city, in the county of New York and State of New York, have invented certain new and useful Apparatus for Recording Electrical Signals, of which the following is a specification.

This invention relates to a method and apparatus for translating radio and telegraphic signals into permanent, visible impressions upon a fluid absorbing surface.

Its object is to provide a simple and efficient means of translating received electrical impulse signals into permanently recorded readable symbols.

The apparatus consists broadly, of a device similar to a pen, equipped with two opposing electrodes, such as a pen point and another metal point located adjacent to the point of the pen with suitable conductive leads to terminals to be connected in an electrical circuit, and means of discharging from one of the electrodes a fluid, through which, under the control of received electrical impulse signals, current is discharged between the electrodes, the fluid being electrochemically responsive by color change, in its path upon the surface upon which it is impressed.

Its operation is based upon the known fact that in certain solutions, such as potassium-iodide, when subjected to an electrical discharge, an electrochemical reaction occurs, changing them from practically colorless substances to those having pronounced colors. This reaction has been utilized in recording telegraph signals, the most common practice being to saturate the paper in the form of a strip, in a solution of potassium-iodide and pass it between two electrodes, between which the electrical impulse signals are discharged. At those intervals in the strip passing during the discharges, permanent dark colored sections of the chemically changed solution are recorded, corresponding to such discharges. This apparatus is not readily portable and the strips must be constantly saturated to be useful.

In accordance with this invention, the apparatus comprises a fluid carrier, similar to a pen, carrying a solution of potassium-iodide, or the like, the pen point acting as an electrode, the opposing electrode being conveniently located, so that current discharging between the two electrodes, passes

through the fluid delivered from its source, at the impression surface. Suitable means are provided for connecting the electrodes to a radio or telegraph line receiving circuit. 60

As the apparatus passes across a paper or other impression surface, or if it is placed in a fixed position and a similar surface passed in contact with it, the fluid therefrom is impressed upon the surface, and the current discharging between the electrodes, in response to incoming signal impulses, changes the fluid from a practically colorless material at the positive electrode, to a dark line on the surface. If the current 70 flows in the form of pulsations, as in telegraph signals, as the electrode passes across the surface, the pulsations are indicated by the short and long line equivalents of the 75 telegraph dots and dashes. Both electrodes must be in contact with the fluid, preferably in its path on the surface. But if it is desired to decrease the surface friction, one of the electrodes can be raised slightly above the surface, so long as it remains in contact 80 with the fluid. By this method of recording, the recording medium is supplied in a moist condition as required.

In order to afford a full understanding of the principles of the invention, one embodiment of the apparatus in an especially desirable practical form, is illustrated in the accompanying drawings, and is hereinafter described in detail for the sake of a concrete 85 illustrative example; but it is to be understood that the invention is not limited to the particular arrangement or specific type of apparatus.

Referring to the drawings,

Fig. 1 shows one form of the apparatus 90 with the wires and terminals for connecting the electrodes in a receiving circuit.

Fig. 2 is a diagram showing the same 95 form of apparatus as a part of a radio receiving circuit.

Referring to Fig. 1, at 1 is a pen point 100 as an electrode connected by wire 5 to one of the terminals 7, and at 2 is placed the opposing electrode, connected by wire 6 to the other terminal at 7 for connection in a receiving circuit. At 3 is one end of a fountain pen, in which the pen point is inserted, and having a hole through it, affording a passage from the fluid reservoir, along the pen point. The wall of the pen is represented by 4.

Referring to Fig. 2, 5 and 6 represent the

lead wires from the fountain pen recorder, connected with the terminals of a radio receiving circuit, and with a vacuum tube amplifier 10, and the input terminals of a 5 transformer 8, connected in a commonly known form of receiving circuit in which 9, 10, 11, 12 and 13 represent the well known elements of such a circuit.

As operated, when the filament of vacuum 10 tube 10, is heated by battery 12, a current will flow through the tube, due to the conduction of the electron stream through the vacuous space, and through the pen electrodes 1 and 2, if a path between is afforded 15 by a moist line of such a solution as potassium-iodide, traced by the pen drawn across the surface. An electrochemical reaction will then occur in the line so traced, changing it from an almost colorless one to 20 a dark brown line which will continue so long as the pen is propelled and the fluid flowing and the current discharging between the electrodes. If the current discharge is interrupted, the dark line is 25 interrupted, the colorless line displacing, or rather, succeeding it.

When the grid in tube 10 is charged negatively by battery 13, it will electrostatically oppose the electron current through 30 the vacuous space between the electron emission element and the plate in tube 10. The potential is so adjusted that normally no current, or an amount insufficient to effect 35 the chemical reaction, will flow through the tube, and therefore through the circuit, so that then, as the pen is passed across the paper surface, only the colorless line appears.

If now a positive potential is applied to 40 the grid circuit, as from the transformer 8,

it will neutralize the negative effect in the grid, and a current will flow in the tube and pen circuit, permitting a recurrence of the electrochemical reaction in the potassium-iodide.

As the primary is connected in an electrical circuit, such as a radio receiving circuit, electrical impulses discharged through the primary will be transferred to the secondary, and when in a positive direction, will 50 cause a flow of current through the circuit when the pen is passed across the surface, affording a path thereon for the discharge, causing an electrochemical reaction in the path of the moist potassium-iodide. Dots 55 and dashes of the signal code will thus occur in the fluid line, directly in response to such signal impulses, yielding a permanent record of incoming messages. To record signals at higher speeds, it is necessary 60 merely to pass the pen over the impression surface at higher speed.

What I claim is,

In combination with a self-feeding pen adapted to contain an electro-chemically responsive color-changing liquid and having an electrically conducting pen point adapted to discharge said liquid upon a contacting surface and to be connected as an electrode in an electrical circuit, another electrically 70 conducting element attached to said pen and adapted to be connected as an opposing electrode in said circuit, and adapted to be, simultaneously with said other electrode, in electrical contact with said liquid discharged 75 from said pen upon said contacting surface.

Signed at New York, in the county of New York and State of New York this 15th day of June A. D. 1922.

SAMUEL RUBEN.
